CARRYING BAG FOR A BOWLING BALL OR SIMILAR ARTICLE

Milton Glantz, Lincolnwood, Ill., assignor of one-half to Samuel N. Glantz, Lincolnwood, Ill.

Filed Sept. 30, 1963, Ser. No. 76,793

Term of patent 14 years

(Cl. D87—5)

FIG. 2

FIG. 1 is a front perspective view of a carrying bag for a bowling ball or similar article, showing my new design, the rear being substantially identical thereto; and

FIG. 2 is a left-side elevational view thereof, the right side being substantially a mirror image thereof.

I claim:

The ornamental design for a carrying bag for a bowling ball or similar article, as shown and described.
